UNITED STATES PATENT OFFICE

2,642,748

MECHANICAL MOVEMENT IN HYDRAULIC MOTORS

Leo Peter Widmer, Winterthur, Switzerland, assignor to Schweizerische Lokomotiv- und Maschinenfabrik, Winterthur, Switzerland

Application December 1, 1949, Serial No. 130,385
In Switzerland January 15, 1949

4 Claims. (Cl. 74—49)

1

My present invention relates to improvements in expandable-chamber motors in which the pistons and cylinders are disposed starlike about a crankshaft in a stationary casing, the cylinders are oscillatable on pins which are parallel to the crankshaft axis, and in which the pressurized fluid is fed to the cylinders through the said pins, while the pistons engage a common ring which is mounted on the crank pin.

In such motors it is known to rigidly secure the said ring to one of the pistons and thus guide the ring by means of one of the swinging cylinders. It further is known to so guide said ring by a separate means that each point thereof describes a circle of a diameter equal to that of the crank circle, i. e. so that all the pistons successively perform exactly the same movement. In the latter case, the torque produced on the crankshaft and the rotary speed of the crankshaft is more uniform than in the former case, but such construction is more expensive and requires more space.

In the motor according to my present invention, the said ring is provided with a series of circumferential V-cuts, of a number equal to that of the cylinders, each cut being engageable with at least one of the pistons. The latter for such purpose are provided with a wedge-shaped foot-portion of which the knife edge is parallel to the axis of rotation of the crankshaft. Such arrangement requires a relatively small space and affords a more uniform rotary speed of the crankshaft.

One form of my present invention is shown in the drawing, in which—

Fig. 1 shows a vertical section on the line I—I of Fig. 2.

Fig. 2 is another vertical section on the line II—II of Fig. 1.

Fig. 3 shows an elevation through a modified piston retaining ring.

Fig. 3A shows a vertical section on the line III—III of Figure 3, and

Fig. 4 is a perspective view of a piston-foot portion conforming to the ring member shown in Figs. 3 and 3A.

In a stationary casing 1, a crankshaft 2 is rotatably mounted by means of antifriction-bearings 3 and 4. The motor torque may be derived from the crankshaft end 5. A ring member 9 is rotatably mounted on a crankpin 7 by means of

a needle-bearing 8, and is provided with nine V-cuts 10 in accordance with the nine cylinders shown. Said cuts are engaged by the wedge-shaped foot-portion 12 of a piston 13 each, the knife edge of portion 12 being parallel to the axis of rotation of crankshaft 2. The piston portion 12 has two lateral shoulders 12a which project from the piston stem. Two ring members 11 engage the shoulders 12a of all the pistons and prevent them from leaving the cuts 10 of ring 9.

In order to permit installation of the ring 9 as an integral member, the crankshaft, as known, in the art, comprises two parts which are interconnected through a screw 6. Each piston 13 is guided in a cylinder 15 which has a crossbore 16 by means of which it is oscillatably mounted on a pin 17 fixed to casing 1. Each pin 17 comprises two longitudinal bores 18, 19 and two bores 20, 21 which open into bores 18, 19 and extend in an approximately radial direction to the center 23 of the stationary casing 1. The said bores 20, 21 in each pin 17 serve for controlling the fluid inflow and outflow to and from the cylinders 15 in a manner similar to that shown and described in my pending U. S. patent application Ser. No. 686,027 of July 24, 1946, now Patent No. 2,507,361, issued May 9, 1950. For such purpose all the bores 18 which at their ends are plugged by caps 22, open to radial ducts 24 which communicate with a first annular chamber 25, the latter being supplied with fluid under pressure from the outside through a pipe 21. All the cylinders 15 disposed on the right of a plane II—II (Fig. 1) therefore communicate with pipe 21, thus being under pressure and producing a torque on crankshaft 2.

The bores 19, which also are plugged by further caps 22, open to radial bores 28 which communicate with a second annular chamber 29 to which a return pipe 30 is connected. An annular cover 31 is secured on casing 1 for closing the chamber 29 toward the inside of the motor. All the cylinders 15 disposed on the left of plane II—II (Fig. 1) communicate with return pipe 30 through the bores and ducts 21, 19, 28, 29 and allow the spent fluid to flow out of the cylinders.

The mode of operation of the motor substantially springs from the above description, it being readily seen that due to the eccentricity of crank pin 7 relative to crank-shaft 2, the latter is ro-

tated counterclockwise (as indicated by the arrow 33 in Fig. 1) when the cylinders to the right of plane II-II (Fig. 1) are supplied with pressure fluid by way of the annular chamber 25. In the crank pin position shown in Fig. 1, the lower wedge-face of the right-hand horizontal piston 13 engages the lower flank 10a of the appurtenant cut 10 and defines the position of ring 9. After the crank has moved through an angle equal to

$$\frac{360^\circ}{9} = 40^\circ$$

in counterclockwise direction, the succeeding piston 13a assumes a similar position relatively to crankpin 7, the wedge of piston 13a abuts against the lower side of the appurtenant V-cut 10, i. e. piston 13a now guides the ring 9. It therefore will be readily seen that during one full revolution of the crankshaft, all the pistons 13 alternatingly guide the ring 9 in like manner as does the right-hand horizontal piston in Fig. 1.

Any tendency of wedge 12 to jump out of cut 10, as induced through a torque acting on the ring 9, is opposed by the fluid pressure acting on the piston. Such tendency also may be opposed through the shape of the cuts in that the angle of the V preferably is made slightly less than 90°.

Figs. 3 and 3A show a modification of the two ring members 11 of Figs. 1 and 2, which also serves for preventing the pistons 13 from jumping the cuts 10. Instead of having a collar 11c of constant thickness (as shown in Figs. 1, 2), the ring member 11a shown in Fig. 3 is provided with milled recesses 11a' of circular cylindrical form. The centers 11a'' of said recesses coincide with the bottoms of the V-notches 10 in ring 9, as shown in Fig. 3. The pistons 13' in such case are provided with two arcuate shoulders 12a' of which the diameter corresponds to that of the recesses 11a' in Fig. 3. In such modification (Figs. 3, 4), the retaining rings 11a must be fixed in the proper position with respect to the star ring 9.

The number of pistons and cylinders may be different from nine. By making the crank pin 7 longer than shown in Fig. 2, a second set of cylinders and pistons may be provided beside the set shown. In such case, the pins 17 may be located, e. g., intermediate the pins 17 of the set shown, on the stationary casing 1.

What I claim as new and desire to secure by Letters Patent, is:

1. In an expansible-chamber type motor in which the pistons and cylinders are disposed starlike about the crank-shaft and the pistons engage a common star ring mounted on the crank pin, the improvement which comprises providing the said star ring with V-cuts of a number equal to that of the cylinders, and wedge-shaped foot portions on the pistons adapted to engage the said cuts, the knife edge of the piston foot portions being parallel to the axis of rotation of the crankshaft.

2. The improvement defined by claim 1, where-in the two sloping edges of each cut includes an angle of less than 90°.

3. A hydraulic motor comprising a crank shaft, a plurality of cylinders disposed starlike about the crankshaft, pistons movable in said cylinders, a star ring mounted on the crank-shaft, each piston being provided with a wedge-shaped foot portion having a knife edge parallel to the axis of rotation of the crankshaft, said star ring being provided with a plurality of V-cuts each engaging the foot portion of one piston, each piston being provided with opposite axially extending shoulders adjacent to the foot portion thereof, and two opposed ring members surrounding the crankshaft laterally of said star ring, said ring members engaging the shoulders of the pistons for retaining the pistons and preventing the wedge-shaped foot portions from jumping out of said V-cuts in the star ring.

4. The improvement, defined by claim 3, wherein each retaining ring is provided with circularly curved recesses, each piston shoulder being of circularly curved form of the same radius as said recesses, the centers of curvature of the said recesses and shoulders being situated on a circle which is concentric with the crankpin and comprises points of the knife edge of the wedge-shaped piston foot portions.

LEO PETER WIDMER.
